UNITED STATES PATENT OFFICE.

ADAM MURCHEY, JOSEPH MURCHEY, AND WILLIAM LUTTRELL, OF GUELPH, ONTARIO, CANADA, ASSIGNEES TO THE NEY MANUFACTURING COMPANY, OF CANTON, OHIO.

TRACK FOR HAY-CARRIERS.

SPECIFICATION forming part of Letters Patent No. 375,089, dated December 20, 1887.

Application filed March 12, 1887. Serial No. 230,590. (No model.) Patented in Canada March 31, 1886, No. 23,737.

To all whom it may concern:

Be it known that we, ADAM MURCHEY, JOSEPH MURCHEY, and WILLIAM LUTTRELL, citizens of the Dominion of Canada, residing 5 at Guelph, in the county of Wellington, in the Province of Ontario, Canada, have invented certain new and useful Improvements in Hay-Carrier Tracks; and we do hereby declare that the following is a full, clear, and exact description of the same, reference being had to the annexed drawings, making a part of this specification, and to the letters and figures of reference marked thereon, in which—

Figure 1 is a view of the track, showing the 15 hangers placed in position for supporting the track and a hay-carrier placed thereon. Fig. 2 is a perspective view of a portion of a track, showing the hanger placed in position for supporting the track. Fig. 3 is a perspective description of the same, reference being had to the annexed drawings, making a part of this specification, and to the letters and figures of reference marked thereon, in which—

The present invention has relation to the peculiar construction of tracks designed for hay elevators and carriers; and its nature consists 25 in providing two pieces of gas-pipe arranged substantially as shown, and in providing a hanger for supporting the track, and in the several parts and combination of parts hereinafter set forth.

Similar letters of reference indicate corresponding parts in all the figures of the drawings.

In the accompanying drawings, A represents the gas-pipes of which the track proper is composed, and which are substantially of the form in the drawings. The gas-pipes A are placed parallel, as shown, and are held at the desired distance apart by the hangers B. The hangers B may be substantially of the form shown 40 in Fig. 1, and, as shown, are provided with the hooks a, located at their bottom or lower ends, and are so formed that the said hooks

will embrace the gas-pipes A, substantially as shown in Figs. 1, 2, and 3. The hangers B are suspended from the rafters of a barn or 45 other suitable frame-work in any convenient and well-known manner.

The gas-pipes A are originally formed in sections of any desired length, said sections being attached together until a track of the desired length is formed. The splicing or connecting block or pin C may be substantially of the form shown in Figs. 2 and 4, and, as shown, the center portions of these splicing or connecting blocks C are provided with the 55 screw-threaded portions a, which fit into a corresponding screw-threaded portion in the ends of the gas-pipes A.

It will be seen that the screw-threaded portion a and the corresponding screw-threaded 60 portions in the ends of the gas-pipes A may be dispensed with and the splicing or connecting blocks C be formed tapering and the gas-pipes driven over said splicing or connecting blocks.

In use the joints of the track proper should 65 be located as shown in Fig. 4, thereby strengthening the track.

Having fully described our invention, what we claim as new, and desire to secure by Letters Patent, is—

The gas-pipes A, arranged parallel with the joints alternating, the connecting or splicing blocks C, and the hangers B, substantially as 70 and for the purpose specified.

In testimony that we claim the above we have 75 hereunto subscribed our names in the presence of two witnesses.

ADAM MURCHEY.
JOSEPH MURCHEY.
WM. LUTTRELL.
